United States Patent Office.

E. O. JONES, OF BRANDON, MICHIGAN.

Letters Patent No. 88,391, dated March 30, 1869.

IMPROVEMENT IN LAND-ROLLER.

The Schedule referred to in these Letters Patent and making part of the same.

To all whom it may concern:

Be it known that I, E. O. JONES, of Brandon, in the county of Oakland, and State of Michigan, have invented new and useful Improvements in Land-Rollers; and I do hereby declare that the following is a full and exact description of the same, reference being had to the accompanying drawings, and to the letters of reference marked thereon.

This invention consists in certain improvements in a form of earth-roller, for which Letters Patent of the United States were granted me on the 21st day of April, 1868, said Letters Patent being numbered 77,048.

It relates more especially to a sectional roller, in which the middle section is located between, and partially in rear of the two side sections, and includes—

First, a peculiar arrangement of the sections, by which the central section, in its revolution, cleans the inner edges of the other two, thus preventing clogging.

Second, a peculiar construction of the flanged rim, which connects the staves of the roller with the head, it being made in sections, for cheapness and convenience.

Third, the construction and arrangement of the frame which supports the middle section of the roller, and permits its weight to be thrown forward, and poised, over the bearings of the outer sections, for facility in turning.

Fourth, the construction and arrangement of the rear side of the central part of the main frame, by which the rear section is sustained when elevated.

In the drawings, in all the figures of which, the same letters refer to identical parts—

Figure 1 is a top view of my improved roller, with the driver's seat and platform removed, showing the main frame, and the arrangement of the sections, the rollers, as, also, part of the markers and connections, and the projections in front of central roller.

Figure 2 shows an end view of the roller, part of the frame being broken away, to show the mode of suspension of the rear section, the driver's seat and platform, and the markers in vertical position.

Figure 3 is an enlarged view of the sectional flanged supporting-ring.

The outer sections of my improved roller are suspended in the frame A, which is composed of side-pieces a, front beam a', and central platform a'', of the width of the middle section, the whole being made of sufficient strength to afford bearings for the sections of the roller, and to sustain the weight and draught.

From the rear end of the side-pieces of the frame A rise two posts, sustaining a cross-beam, c, on which is the driver's seat, the whole being of sufficient height to clear the rear, or middle section in its utmost elevation.

To these side-bars is also pivoted the frame which supports the rear section. It consists of two vertical posts d d, pivoted, to permit vibration, a cross-beam,

E, and the projecting arms f f, in the lower ends of which are the bearings of the central section.

The posts d d are pivoted, in this case, a little in rear of the bearings of the outer sections, and the arms f f are so constructed, being of bent form, as to hold the central section, when the posts d d are vertical, in rear of the bearings of the latter, so that, when the posts d d are tipped forward by the depression of the platform, the central section of the roller shall be, by the same motion, elevated and brought forward.

It is not absolutely essential that the posts d d should be pivoted at any particular point upon the main frame. The pivot-point must depend somewhat upon the position of the middle section of the roller. If this be nearly in line with the outer sections, the fulcrum of the levers must necessarily be moved forward, for convenient operation.

Upon the rear part of the central platform a'' of the main frame A are arranged projections Y Y, on which the central section rests when thrown forward. If desired, the rear part of the frame may be extended backward for this purpose, far enough to receive the roller, the upper side being bevelled, or otherwise arranged, to permit the roller to pass easily upon it.

Any other suitable arrangement for the purpose may be made. It is only necessary that the rear section shall be operated in such manner that its weight may be borne by the bearings of the outward sections, and the swinging frame thus be relieved from all strain during the operation of turning.

There is also a standard, G, to furnish support for the platform.

From the posts b b, also, project rearward, two arms h h, which carry on their ends a cross-bar, K.

To this cross-bar are attached the markers l l l, by means of small rollers, which have their bearings in short projecting arms from the bar K.

Directly to the markers is attached, by cord or links, a rod, extending across the whole, and to the centre of this, by a rope or chain, a lever, which passes over the top of the frame, and is convenient to the hand of the driver, and which may be held under a catch, if desired. By depressing or elevating this lever, the markers are raised or lowered.

These markers may be attached to the bar in other ways, without material change.

The sections of my roller are of peculiar construction, shown more particularly in figs. 2 and 3.

They consist of a head, or disk in each end, to which are fixed flanged rings. In these rings are two features. They consist of two flanges, at right angles with each other, one of which rests on the head, or disk, and is bolted thereto, and upon the other rest, and are bolted, the ends of the exterior planking, or staves.

As these flanged rings, if cast whole, are rendered useless by an imperfection in any part, I have devised a sectional construction, as shown in the drawings, cast-

ing the ring usually in quarter-sections, for cheapness and convenience.

The central section, which has its axis of rotation far enough behind the axes of the outer sections to permit the section to be raised in turning, is yet arranged to roll between the outer sections. It moves near to, or in contact with these sections, and the effect of the arrangement is to cause the forward part of the ends of the central section, which are in contact with the inner ends of the rear part of the outward sections, to move downward, while that part of the outer, moves upward and the reverse, thus making the sections in contact constantly move in opposite directions.

The rear section may be hung between the outer sections at any point in rear of the lines of the bearings of the latter, as the same result will be produced so long as the lines of their circumferences cut each other.

The thills, or shaft, are attached to the forward part of the frame, in any suitable manner.

The operation of this improved roller is as follows:

The described arrangement of the sections, while it permits the central section to be raised, in order that the roller may turn more easily on the outer, also effects, by the contact of ends and the opposite motions, that the sections keep each other from all clogging, and removes a serious objection heretofore existing in sectional rollers.

The arrangement of the rear section upon the frame, and the location of the upper platform, permit the sec-

tion to be raised and thrown forward by the weight of the driver, stepping on the platform. The section is thrown against the two pins $X Y$, or other similar arrangement, and thus the weight of the whole is poised over the axes of the forward sections, and the roller easily turned, without throwing undue weight on the horses.

Having thus fully described my improvements,

What I claim as my invention, and desire to secure by Letters Patent of the United States, is—

1. The arrangement of the roller-sections in such relation to each other that the lines of their circumferences cut each other, and thus free each other from clogging, substantially as set forth.

2. In combination with the central section of the roller, the pins, or other supporting-arrangements upon which it rests when raised, as and for the purpose described.

3. The rear, or middle section of a sectional roller, when attached, by means of connections, as described, pivoted to any part of the main frame, substantially as described.

This specification signed and witnessed, this 26th day of June, 1868.

E. O. JONES.
